COMBINED RECORD PLAYER AND SPEAKER SYSTEM

Arthur Steidinger, St. Georgen, Black Forest, Germany

Application May 22, 1958, Serial No. 51,022

Term of patent 3½ years

(Cl. D56—4)

Fig. 1 is a front perspective view of a combined record player and speaker system, showing my new design;

Fig. 2 is a rear perspective view thereof; and

Fig. 3 is a front perspective view thereof in operable position.

The dominant features of my design reside in the portions shown in full lines.

I claim:

The ornamental design for a combined record player and speaker system, as shown and described.
